UNITED STATES PATENT OFFICE.

LOUIS O. BROWN AND LEONHARD BAUROTH, OF TOLEDO, OHIO, ASSIGNORS TO THE METALLIC BARREL COMPANY, OF CHICAGO, ILLINOIS, A CORPORATION OF MAINE.

CLOSURE FOR THE OPENINGS OF CONTAINERS.

1,090,824.

Specification of Letters Patent. Patented Mar. 17, 1914.

Application filed June 26, 1909. Serial No. 504,453.

To all whom it may concern:

Be it known that we, LOUIS O. BROWN and LEONHARD BAUROTH, citizens of the United States, and residents of Toledo, in the county of Lucas and State of Ohio, have invented a certain new and useful Closure for the Openings of Containers; and we do hereby declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to closure means for the openings of metallic packages and particularly to packages of this class adapted for the packing of nails, paint, white lead or other matter.

The object of our invention is the provision of a simple, improved and highly efficient closure of this class, which is strong and durable in its construction, inexpensive of manufacture, and capable of easy and quick application to a vessel or package for which it is adapted.

The operation, construction and arrangement of the parts of the invention are fully described in the following specification, and while the invention in its broader aspect is susceptible of numerous modifications, a preferred embodiment of the same is illustrated in the accompanying drawings, in which,—

Figure 1 is a plan view of a closure embodying the invention with the split locking-ring contracted. Fig. 2 is a partial central longitudinal section of the upper portion of a package with a closure set in the opening thereof but not locked against removal. Fig. 3 is a side elevation of the same with a portion in section and the closure shown as locked against removal, and Fig. 4 is an enlarged section of a portion of the package and closure in locked engagement.

Referring to the drawing, 1 designates the side casing or wall of a sheet metal package, such, for instance, as a keg or the like, an end of which is provided with an opening, preferably round, for the reception of a closure-member 2 of sheet-metal, which opening may be coextensive with the end of the package, as shown, or of less diameter, than such end if desired. The end edge

of the casing 1, which forms the wall of such opening in the present instance, is beaded, as at 3, around a reinforcing wire with a portion of the bead disposed on each side of the casing to provide inner and outer annular ribs or shoulders thereon.

The closure 2 is drawn in pan-shape to adapt it to fit within the package opening with its side wall 4 in frictional contact with the inner side of the bead 3 and the outer edge thereof rolled outwardly and downwardly, as indicated at 5, to adapt it to hook over the head. After the closure has been inserted into the opening the lower or inner portion of the side wall 4 of the closure is spun or expanded in any suitable manner under the inner edge of the rib or shoulder formed within the casing by the bead 3 to prevent a withdrawal of the closure from the opening, as is apparent by reference to Figs. 3 and 4.

The closure wall 4 having been expanded to coöperate with the bead 3 to retain the closure in the package opening, a split spring-ring 6 is sprung within the annular groove thus formed within the closure and effectually serves to prevent a contraction of such expanded portion, which might otherwise occur under the stress of internal pressure on the closure. The rod or band forming the ring 6 is preferably of suitable length for its ends to meet, or substantially so, when sprung within its receiving groove in the closure so that the abutting contact of such ends will resist a contraction of the ring. If desired the ends of the ring may be provided with a tongue and a groove complementary to each other, as shown at 6 Fig. 1, which interlock when the ring is sprung in place within the closure.

The outer edge 7 of the closure wall 4 is preferably, but not necessarily projected below the bead 3 to adapt it to be drawn under the same in opposition to the expanded portion of the closure, as shown in Figs. 3 and 4. A binding-wire 8 is then drawn tightly around the contracted edge of the closure and may have its ends twisted or otherwise secured together, as indicated at 9 Fig. 3, thus coöperating with the bead 3 and spring-ring 6 to securely retain the closure to its seat in the opening.

The bead 3 is preferably formed by rolling the end edge of the body wall 1 outwardly around a core wire, which has its

internal diameter less than that of the end opening prior to the forming of the bead and its external diameter greater than that of the end edge of the body, whereby to 5 form a strong and durable bead which provides both internal and external ridges at the end of the body.

The exceedingly rigid end structure, which our invention provides and which is 10 so important in packages of this character to enable them to withstand the hard usage and varying stresses to which they are subjected, is due very largely to the coöperative action of the several parts employed, 15 as the ring 6 coöperates with the interposed layers of metal to resist the compressing action of the band 8, and vice versa, and the rigid construction of bead, which forms the inner and outer ridges, coöperates very materially 20 with the members 6 and 7 and the side wall of the closure to provide a package the chime portion of which is of the strength required to stand the tests to which such packages are subjected.

25 It will be apparent that we have not only provided a closure which is exceedingly strong and durable in its construction and simple of application, but one which forms a close and air-tight joint with the wall of 30 the opening and is therefore adapted for use in any connection in which sealed joints are essential.

We wish it understood that our invention is not limited to any specific construction 35 or arrangement of the parts except in so far as such limitations are specified in the claims.

Having thus described our invention, what we claim as new, and desire to secure by 40 Letters Patent, is,—

1. In a container of the class described, a ring having an end edge of the container wall wrapped therearound and coöperating

therewith to form a chime with an internal and external ridge, a pan-like closure fitted 45 into said chime with its bottom disposed below the chime ridges and having its side wall embracing said chime with opposing portions drawn under the respective ridges, an expanding ring-like member disposed 50 within the closure and seating within the portion thereof which is expanded outwardly under the inner chime ridge, and a ring-like member seating within the portion of the closure wall which is drawn inwardly 55 under said external ridge, said members coöperating with each other and with the bead ring to form a rigid chime.

2. A container of the class described having an end edge of its body wall beaded to 60 form its chime with an internal and external ridge, a pan-like closure fitted into said chime with its bottom disposed below the chime ridges and having its side wall embracing said chime with opposing portions 65 drawn under the respective ridges in opposing contact with the container wall, an expanding ring disposed within the closure and seating within the expanded portion of the closure under the internal ridge, and a 70 ring-like band drawn closely around the inwardly drawn portion of the closure wall whereby said expanding ring and band cause the portions of the closure wall against which they respectively seat to be held in 75 opposing contact with the container wall below the edge bead thereof.

In testimony whereof we have hereunto signed our names in the presence of two subscribing witnesses.

LOUIS O. BROWN.
LEONHARD BAUROTH.
